UNITED STATES PATENT OFFICE.

HENRY WILLIAM BRAHE, OF PORT PIRIE, SOUTH AUSTRALIA, AUSTRALIA, ASSIGNOR
TO BROKEN HILL ASSOCIATED SMELTERS PROPRIETARY LIMITED, OF PORT PIRIE,
SOUTH AUSTRALIA, AUSTRALIA.

HANDLING OF RETORTS USED IN THE PRODUCTION OF SPELTER.

1,323,575.

Specification of Letters Patent.

Patented Dec. 2, 1919.

Application filed February 27, 1918. Serial No. 219,509.

To all whom it may concern:

Be it known that I, HENRY WILLIAM BRAHE, foreman, a subject of the King of Great Britain, residing at Port Pirie, in the 5 State of South Australia, Commonwealth of Australia, have invented certain new and useful Improvements in the Handling of Retorts Used in the Production of Spelter, of which the following is a specification.

10 This invention relates to improved means for the handling of retorts used in the production of spelter or commercial metallic zinc and refers to means whereby a considerable saving of labor is effected with a corresponding reduction in working costs and further whereby certain arduous operations as at present conducted are avoided.

15 In the metallurgy of zinc at present conducted the oxidized zinc ore mixed with a reducing agent such as coke is heated in retorts and the metallic zinc vapor therefrom is condensed in the form of spelter.

20 These retorts are made of fire clay and after being molded and while still in the 25 "green" state are placed in a furnace or kiln in which they are stacked in a vertical position and where they are suitably burned. These retorts require to be removed from this furnace while red hot and transferred 30 to the distillation furnace in which they are set substantially horizontal. The operation of handling these retorts is usually effected by hand and involves great care and the employment of a gang of men, usually from 35 3 to 4, and the work is arduous and unpleasant.

40 The object of this invention is to provide improved means for the handling of retorts used in the production of spelter or metallic zinc whereby certain mechanical devices are afforded for the proper handling and support of the said retorts thereby dispensing with a proportion of the labor employed and avoiding the arduous part thereof.

45 I accomplish this object by providing improved means for the support and conveyance of these retorts which comprise a long lifting bar or lever pivoted or supported at or about its center to a traveling carrier the 50 forward end being adapted to be inserted into the interior of the retort to support the same during transport and positioning. The rearward end of the said lever may be provided with a balance weight slidably thereon while the aforesaid carrier is so mounted

that it may be conducted to and from any one of the preheating kilns and to and from any one of the distilling furnaces.

55 In order that the invention may be readily understood reference will now be had to the accompanying sheets of explanatory drawings wherein—

60 Figure 1 is a view in side elevation of an apparatus constructed in accordance with the present invention showing a retort in section supported by the same.

65 Fig. 2 is a view in plan of a portion of the apparatus shown in Fig. 1.

70 Fig. 3 is a view in perspective showing a modified form of apparatus.

75 Fig. 4 is a view in sectional end elevation of the modified form of apparatus on the plane 4—4 of Fig. 3.

80 In these drawings the letter *a* designates a portion of an overhead trolley track or runway which is adapted to support a carrier or telpher *b* and is arranged to pass from above the front of the kilns to above the front of the furnace. The kilns and furnaces are not shown in the drawings as they do not form part of the invention which can be used with any ordinary form of kiln or furnace. The overhead carrier *b* supports a hoist *c* to which the lifting bar or lever *d* is attached by means of a chain *e* so that it may be raised and lowered to suit the different vertical positions in which the retorts have to be placed. The hoist can be operated by a chain *e'*. The chain *e* is secured to the center or approximately to the 85 center of the lifting bar *d* by means of a swivel connection *f* which permits of the said lifting bar being swung around quite freely in any direction.

90 The lifting bar or lever *d* can be made of any approved shape in cross section and is formed on the top and forward end with a curved seat *d'* adapted to fit the inside contour of the retort *g* being handled. When handling "green" retorts the lifting bar or lever *d* would preferably be formed of wood and if necessary padded with felt, leather or the like *g'*—see Fig. 3 of the drawings.

95 The rearward portion of the lifting bar or lever *d* has a counter-weight *h* slidably mounted thereon to counter-balance the weight of the retort when the same is being transported and to counterbalance the overhanging bar *d* when no load is being carried. For this purpose the said counter-weight is 100 105 110

adjustable in position and can be securely fastened in its adjusted position on the bar or lever by means of a locking lever or screw *i*.

5 The rear end of the lifting bar or lever *d* is fitted with handles *j* which permit of the said lifting bar or lever being conveniently controlled when supporting a retort. A stop *k* is fitted to or adjustably secured by any 10 approved means to the top of the lifting bar or lever to prevent the same being thrust too far into the retort and cause damage to the end thereof. This stop *k* is not necessary if the bar is sufficiently long and is 15 provided with a flanged end adapted to engage the butt end of the retort.

In the modified form of apparatus shown 20 in Figs. 3 and 4 of the drawings the swivel connection *f* is pivotally secured to the center of a saddle *l* through which the lifting bar is adapted to slide endwise. The bottom of the saddle *l* is provided with antifriction members *m* which insure freedom of movement to the bar or lever when supporting 25 a retort and being moved endwise therein. A stop *n* is fitted adjustably to the lifting bar or lever *d* or other equivalent device which is adapted to limit the distance to which the said bar or lever may enter the retort. A 30 second stop *o* is mounted adjustably on the lifting bar or lever *d* and this said stop is secured in any desired position by tightening up a lever screw *p*. The position of the stop *o* determines the extent to which the bar or lever *d* can be thrust through the saddle *l*.

The forward end of the lifting bar or lever can be enlarged as shown in Fig. 1 to minimize the danger of the butt end of the retort being knocked out or damaged 40 should the said bar or lever be thrust forcibly thereagainst.

45 My improved method of handling the retorts while in a "green" state and when being moved to and from the kilns in a heated condition comprises a new series of consecutive operations. The "green" retorts are carried by the lifting bar and carrier and placed in a horizontal position in a pre-heating kiln adapted therefor. When 50 the retorts are red hot they are moved from the kiln by inserting the forward end of the lifting bar or lever therein and adjusting the counter-weight to balance the weight of the said retort. The retort is withdrawn 55 from the kiln and conveyed to the distillation furnace by operating the carrier or telpher and then the retort is placed in position in the furnace, by unlocking the lever *p* and pushing the retort into position 60 by causing the rod to move endwise on the anti-friction members, the weight of the retort being carried by the saddle thereby minimizing the labor of placing it in position.

When the retort is placed in position it 65 is charged and luted to its respective condenser. The invention is exceedingly simple in construction and can be operated by two men with comparative ease.

70 Various other modifications and alterations may be made in the invention, in the direction indicated, without departing from the spirit and scope of the same, and I therefore, do not wish to be understood as limiting myself to the exact constructions illustrated or to the precise terms employed in 75 the description.

I claim:

1. In an apparatus for use in handling retorts a saddle suspended at or about its 80 center from a movable support and a lifting bar or lever supported by and adapted to move endwise in the saddle whereby the retort can be pushed into a furnace while the weight is still supported by the saddle. 85

2. In an apparatus for use in handling retorts used in the production of spelter, a saddle having a swivel support at or about its center from a traveling hoist, antifrictional rollers or balls in the bottom of the 90 saddle a lifting bar or lever passing through the saddle and resting on the antifrictional rollers or balls therein, and means for limiting the movement of the lifting bar or lever through the saddle, substantially as described. 95

3. In an apparatus for use in handling retorts used in the production of spelter, the combination of a saddle having a swivel support at or about its center from a traveling hoist, a lifting bar or lever supported by and adapted to be moved endwise through the saddle, one end of the lifting bar shaped on its top to the contour of the 100 interior of a retort, an extension or handles 105 on the opposite end of the lifting bar or lever, and an adjustable stop or fastening means for limiting the movement of the lifting bar or lever in the saddle, substantially as described. 110

4. In an apparatus for use in handling retorts used in the production of spelter, the combination of a saddle having a swivel support at or about its center from a traveling hoist, a lifting bar or lever supported by and adapted to be moved endwise through the saddle, one end of the lifting bar shaped on its top to the contour of the interior of a 115 retort, a counterweight mounted adjustably on the opposite end of said lifting bar or lever, and handles on the lifting bar or lever for operating the same. 120

In testimony whereof I affix my signature in presence of two witnesses.

HENRY WILLIAM BRAHE.
